DRINKING STRAW DISPENSER

George W. Pace, Elwood, Ind.

Application July 17, 1940, Serial No. 345,905

7 Claims. (Cl. 312—84)

This invention relates to means for dispensing drinking or soda straws and has for a primary object the provision of a structure whereby the straws may be dispensed one or more at a time to be placed directly into a bottle ready for use without coming into contact at any time with the operator's hands. It is known that heretofore soda straws have been dispensed directly from packages and hoppers but in all of the known structures, the operator had to receive the straws in his hands and transfer them to the glass or bottle in which the straws were to be used. The invention eliminates this undesirable feature in a very simple structure automatically operated simply by entering the neck of a bottle or a container into the mouth of the opening through which the straws are to be dispensed.

The straws may be dispensed either directly from the original package or may be dumped into a hopper and dispensed therefrom without affecting the invention.

The foregoing and many other objects and advantages of the invention will become apparent to those versed in the art in the following description of one particular form of the invention as illustrated in the accompanying drawings, in which

Fig. 1 is a front view in elevation of a structure embodying the invention with the front wall partially broken away;

Fig. 2, a vertical section on the line 2—2 in Fig. 1; and

Fig. 3, a detail in section on the line 3—3 in Fig. 1.

Like characters of reference indicate like parts throughout the several views in the drawings.

In the upper end of a housing, generally indicated by the numeral 10, is positioned a trough 11 transversely thereacross terminating in a lower floor 12 across which extends a slot 13. The trough 11 is made to be sufficiently long to receive therein at least the corner of a package of straws that has been opened along that corner to permit the straws to drop down on the floor 12. The length of the trough 11 is, of course, sufficiently long to accommodate the lengths of straws to be used. In the form herein shown, the trough 11 is attached to the housing 10 in any suitable manner, herein shown as by a bracket 14, the upper end of which is turned over to engage with an inturned flange 15 of the housing wall.

Bearing plates 16 and 17 are fixed to the outer ends of the trough 11 and project downwardly therebelow to receive therethrough the axle 18.

of a roller 19. This roller 19 extends entirely across the under side of the trough floor 12 to form normally a stop across the slot 13 to prevent straws from feeding therefrom. This roller 19 carries a longitudinal groove 20 that is normally presented along the slot 13 so that one or more straws may drop therein, the number of straws depending upon the dimensions of the groove 20. That is, when the roller is presented, as indicated in Fig. 2, straws may drop through the slot 13 into the groove 20 as indicated but further feeding will be arrested. The upper edge of the roller 19 is substantially tangential with the under side of the floor 12.

Secured to the axle 18 at one end thereof is a rocker lever 21, herein shown as being adjustably attached to the axle to any desired fixed position therearound. A connecting rod 22 has its upper end rockably connected to the lever 21 and its lower end rockably connected to the transverse lever 23 which is mounted within the housing 10 upon a suitable bracket 24 extending from the wall of the housing.

In the under side of the housing 10 is a hole through which a thimble 25 is free to reciprocate with a vertical travel. This thimble 25 is secured to a foot 26 of the arm 27 that is carried upwardly and rockably engaged with the lever 23 on the opposite side of the pivot 28 from the connection therewith by the connecting rod 22, Fig. 1. The juncture of the thimble 25 with the foot 26 may be formed in any suitable manner, such as by welding. In the present form, the foot 26 extending along the side of the thimble 25 comes into abutment with a stop 29 comprising an upturned portion of the floor of the housing 10. A spring 30 fixed to the lever 23 and a bracket 31 on the housing 10 normally rocks the lever 23 to hold the foot 26 against the stop 29. The various levers and connections therebetween as just described are so proportioned and adjusted that when the foot 26 is resting against the stop 29, the roller 19 will be maintained by the spring 30 in that position indicated in Fig. 2 wherein the groove 20 is uppermost and in alignment with the trough slot 13.

Under the roller 19 and toward one end thereof is mounted a funnel 32 with its small end in axial alignment with the thimble 25 and spaced somewhat above the normal lower position of the thimble. One side and slightly above the upper end of the funnel 32 is mounted a finger 33 to extend transversely across and directly under the roller 19. This finger 33 is mounted

at least slightly to one side of the longitudinally center of the roller 19.

Within the thimble 25 is an abutment 34, herein shown as consisting of an annular ring. In using the structure thus described, the upper end of a container, herein shown as the neck 35 of a bottle, Fig. 1, is inserted into the thimble 25 from its under side to have the mouth of the bottle come into contact with the abutment 34, whereupon the bottle is lifted to overcome the spring 30 and through the lever system rock the roller 19 to carry the straw or straws contained in the groove 20 around to one side to permit those straws to drop out of the groove. The straws dropped will, of course, strike the finger 33 in the path thereof and since this finger 33 is to one side of the centers of those straws, the longer ends thereof will continue to drop and since these longer ends are over the mouth of the funnel member 32, they will drop on down therein and be rocked around to approach vertical positions as they continue to fall and pass on down through the lower opening in the funnel 32 to drop on down into the mouth of the bottle 35, whereupon the bottle may be removed with the straws positioned therein.

Thus it is to be seen that the straws are not only dispensed one or more at a time as may be desired but that they are also turned from horizontal to inclined positions approaching the vertical so that they may drop in first into the container of the liquid in which the straws are to be used, all without being exposed to handling or exposed to the atmosphere outside of the housing 10.

The housing 10 is provided with a suitable cover 36, herein shown as being connected therewith by the hinge 37. The cover 36 in the present form is shown as being arched upwardly so that a package of straws may be placed diagonally in the trough 11 and still be covered over. The package in any event is placed directly into the trough 11 to be aligned thereby and then the cover 36 is closed for sanitary purposes.

While I have herein shown and described my invention in the one particular form, it is obvious that structural changes may be employed without departing from the spirit of the invention and I, therefore, do not desire to be limited to that precise form beyond the limitations as may be imposed by the following claims.

I claim:

1. In a dispenser for delivering straws directly into a bottle, the combination with a straw hopper formed to retain straws in parallel alignment and a shiftable member under the hopper having a slot therealong restricted in cross-sectional area to receive a selected number of straws from the hopper; of an arm, means for shifting said shiftable member to dump straws from said slot onto said arm, said arm being positioned to be contacted by the straws at a position removed from the longitudinal centers of the straws whereby the longer ends of the straws tend to drop by gravity, means for receiving the falling straws tending to direct them toward vertical positions, said receiving means having an opening at its lower end, a bottle mouth receiving member interconnected with and adapted to actuate said slotted member shifting means upon raising the bottle mouth receiving member, said bottle mouth receiving member aligning the mouth of a bottle carried thereagainst with said opening, whereby the straws upturned by said arm are directed into the mouth and drop into the bottle.

2. In a dispenser for delivering straws directly

- 75 into a bottle, the combination with a straw hopper formed to retain straws in parallel alignment and a shiftable member under the hopper having a slot therealong restricted in cross-sectional area 5 to receive a selected number of straws from the hopper; of an arm, means for shifting said shiftable member to dump straws from said slot onto said arm, said arm being positioned to be contacted by the straws at a position removed from 10 the longitudinal centers of the straws whereby the longer ends of the straws tend to drop by gravity, means receiving the falling straws tending to direct them toward vertical positions, said receiving means having an opening at its lower end, a bottle mouth receiving member interconnected with and actuating said slotted member shifting means upon raising the bottle mouth receiving member aligning the mouth of a bottle carried there- 15 against with said opening, whereby the straws upturned by said arm are directed into the mouth and drop into the bottle, said bottle mouth receiving member consisting of a collar and a bottle abutment therewithin.
- 15 20 25 30 35 40 45 50 55 60 65 70 75 80 85 90 95
3. In a dispenser of soda straws, or rod-like members and the like from a hopper carrying the members in substantially horizontal parallel alignment, the hopper having a slot through which the members may drop, a roller under the hopper slot having a longitudinal slot therealong to receive one or more of said members therein in accordance with the depth and width thereof, means for rocking the roller to dump the members from said slot, and an arm mounted adjacent said roller to be in the path of the members falling from the roller slot, said arm being mounted to one side of the longitudinal centers of the members whereby the members are rocked from their horizontal positions to have corresponding ends thereof directed downwardly.
4. In a dispenser of soda straws, or rod-like members and the like from a hopper carrying the members in substantially horizontal parallel alignment, the hopper having a slot through which the members may drop, a roller under the hopper slot having a longitudinal slot therealong to receive one or more of said members therein in accordance with the depth and width thereof, means for rocking the roller to dump the members from said slot, and an arm mounted adjacent said roller to be in the path of the members falling from the roller slot, said arm being mounted to one side of the longitudinal centers of the members whereby the members are rocked from their horizontal positions to have corresponding ends thereof directed downwardly, a ring mounted below said arm, and guide means receiving said members as they drop from said arm and directing them toward said ring through which the members may slide downwardly end first.
5. In a dispenser of soda straws, or rod-like members and the like from a hopper carrying the members in substantially horizontal parallel alignment, the hopper having a slot through which the members may drop, a roller under the hopper slot having a longitudinal slot therealong to receive one or more of said members therein in accordance with the depth and width thereof, means for rocking the roller to dump the members from said slot, and an arm mounted adjacent said roller to be in the path of the members falling from the roller slot, said arm being mounted to one side of the longitudinal centers of the members whereby the members are rocked from their horizontal positions to have corresponding ends thereof directed downwardly, a ring mounted below said arm, and guide means receiving said members as they drop from said arm and directing them toward said ring through which the members may slide downwardly end first.

sponding ends thereof directed downwardly, a ring mounted below said arm, and guide means receiving said members as they drop from said arm and directing them toward said ring through which the members may slide downwardly end first, said guide means comprising a funnel-like member opening at its lower smaller end through said ring.

6. In a dispenser of soda straws, or rod-like members and the like from a hopper carrying the members in substantially horizontal parallel alignment, the hopper having a slot through which the members may drop, a roller under the hopper slot having a longitudinal slot therealong to receive one or more of said members therein in accordance with the depth and width thereof, means for rocking the roller to dump the members from said slot, and an arm mounted adjacent said roller to be in the path of the members falling from the roller slot, said arm being mounted to one side of the longitudinal centers of the members whereby the members are rocked from their horizontal positions to have corresponding ends thereof directed downwardly, a ring mounted below said arm, and guide means

receiving said members as they drop from said arm and directing them toward said ring through which the members may slide downwardly end first, said guide means comprising a funnel-like member opening at its lower smaller end through said ring, means for rotating said roller, said ring being interconnected with said rotating means to reciprocate in alignment with said funnel opening.

10 7. In a dispenser of soda straws, toothpicks, or rod-like members from a hopper arranged to carry a supply of the members in substantially horizontal alignment to drop through a slot along the underside of the hopper, a rockable member under the hopper slot formed to receive therein one or more of the hopper carried members, means for rotating the rockable member to dump the hopper discharged members therefrom, and fixed means located to one side of the longitudinal centers of said members and in the path of the falling members for tilting them from horizontal positions by reason of those members rocking thereover under influence of gravity.

GEORGE W. PACE.
